J. T. JANETTE

SAFETY DEVICE FOR FUEL SYSTEMS

Filed Feb. 6, 1926

Fig. 1.

Inventor:
John T. Janette,
By Glenn S. Noble
Atty.

UNITED STATES PATENT OFFICE.

JOHN T. JANETTE, OF CHICAGO, ILLINOIS.

SAFETY DEVICE FOR FUEL SYSTEMS.

Application filed February 6, 1926. Serial No. 86,487.

Liquid fuel combustion systems, or oil burning systems, such as are more or less commonly used for heating houses, buildings or for other similar purposes are usually supplied with either gravity tanks, vacuum tanks or auxiliary tanks into which fuel is pumped before it is delivered to the burner. The oil is carried from such tank to the burner through the supply pipe. If an ordinary gravity tank is used, which tank may be filled by hand or else have the oil pumped into the same, and if the supply pipe becomes broken, all of the oil in the tank is liable to be discharged onto the floor of the basement or room in which the burner is located. If a vacuum tank or auxiliary supply tank is used, into which the oil is pumped or forced for a storage tank by automatic means, and the supply pipe to the burner leaks or becomes broken, then all of the oil in the storage tank is apt to be pumped into the burner room. In either event, there is not only loss of oil but a consequent liability of damage on account of fire, if the oil in the basement or burner room becomes ignited.

The present invention relates to means whereby, if there is a broken or leaky supply pipe to the burner, or an excessive demand from anyone of such tanks or any similar tank, the outlet from the tank will become closed and will remain closed until opened by manual means.

The objects of this invention are to provide an improved safety device for liquid fuel or oil burning systems; to provide means for preventing the discharge of an excessive amount of oil or other similar material from a tank or receptacle; to provide a discharge outlet with means whereby the outlet will be automatically closed when the discharge exceeds a predetermined amount or rate; to provide a tank or the like with a float controlled outlet valve which will be in normally raised position, but which will move to closing position, under predetermined conditions, to provide a float operated closure for tanks which will keep the outlet open during normal operation, but which will close the outlet under excessive demand; and to provide such other advantages and improvements as will be described more fully hereinafter.

In the accompanying drawings illustrating this invention;

The figure is a sectional elevation of a supply tank or system showing one form of my invention, parts being shown diagrammatically for convenience in illustration.

In the construction shown in the figure, 5 represents a storage tank such as is usually located outside of a building, and 6 represents an auxiliary tank such as is usually located within the building or near the burner. The fuel is pumped from the tank 5 into the tank 6 by any suitable pump such as shown as 7, this pump being driven by an electric motor 8. The fuel is drawn through an intake pipe 9 and discharged through the pipe 10. The motor 8 is controlled by a switch 11 which is actuated by a float 12 in the usual manner so as to start the motor when the oil in the tank reaches a predetermined low level and to stop the motor when the oil in the tank reaches a predetermined high level.

The tank 6 has an outlet or supply pipe 13 which leads to the burner (not shown). This pipe engages with a flange or fitting 14 which is secured to the bottom of the tank and which has a valve seat 15 at the top. The valve 16 which coacts with the seat 15 may be of any suitable type, as for instance a flat disk with a facing of leather or other suitable material. This valve is connected by means of a valve stem 17 with a float 18 which has an upwardly extending rod 19. The valve stem and rod are guided in bearings 20 and 21 which are carried by a bracket 22 which is secured to the flange or coupling 14. Any suitable means may be provided for raising the valve after it has moved to closed position, but in the arrangement shown, I provide a collar 23 on the rod 19 which is adapted to be engaged by a wire or handle 24 which projects upwardly through the top of the tank 6.

During the normal operation of the device, the float and valve 16 will remain in raised position, these parts being so proportioned that the float will have sufficient buoyancy in the liquid with which the tank is filled, to hold the valve off its seat. As long as the liquid passes out through the pipe 13 at a normal rate and the pump oper-

ates to keep the tank 6 filled to its normal level, the valve will remain opened. The tank discharge valve 16 is held in a position sufficiently close to its seat that it will be drawn down onto its seat when the flow exceeds a predetermined rate. Such excess flow, as hereinbefore suggested, may occur through the leaking or breaking of the pipe 13 or may occur from any cause which permits a higher rate of flow than that for which the valve is set. If the pump continued in operation after the discharge valve is closed, the tank would be gradually filled to its normal level, but the float and valve would remain in lowered position with the outlet closed, so that no more fluid would be discharged from the tank. Of course, when the liquid in the tank reaches its uppermost position, the motor will be stopped by its automatic control mechanism. When the outlet valve 16 is closed, no more fuel will be discharged from the tank and the ports will remain in such position until the outlet valve is again raised manually, as by means of the wire handle 24. Thereupon, the oil would be permitted to flow from the tank again in the normal manner and the valve and float would remain inoperative until another excessive demand occurred. The operation of the valve is of course somewhat similar to that of a flush valve, but in this case the valve is normally opened, while in a flush tank the valve is normally closed.

In this connection, it will be noted that if the discharge pipe 13 such as ordinarily provided in systems heretofore used became cracked or broken so that the leakage therefrom was somewhat less than the capacity of the pump, the pump might continue in operation and a large amount of oil be discharged without lowering the level of the liquid in the tank 6 beyond its normal operating levels. In order to prevent such an occurrence, the position of the valve 16 as shown herein with respect to the valve seat 15 may be regulated or adjusted so that the valve and float will be drawn down to closed position by any predetermined amount of excess flow through the outlet pipe. In other words, if the valve 16 is raised but a slight distance above the outlet opening, a comparatively slight excess discharge will draw the valve and float down to closed position. However, if the valve 16 is raised a greater distance off from the seat, then a greater excess flow will be required to draw it and its float down, but by regulating this distance, the stoppage of the outlet may be regulated in accordance with the flow instead of depending upon the lowering of the level of the oil to such a point that the float will descend by gravity, as above described. However, it will also be noted that the closing action of the valve is also dependent upon the buoyancy of the float, and it is as-

sumed that for the above operations, the float will be of suitable proportions with respect to the valve, which under ordinary conditions would mean that the float and attached parts, when in raised position, will be in a substantially balanced position, or such that the float merely holds the valve raised.

With this description, it will be seen that I provide means for protecting various types of fuel burning systems or means whereby systems or tanks may be protected against undue or excessive discharge beyond a predetermined rate, and, it is apparent that various changes may be made in order to adapt the invention to different conditions. Therefore, I do not wish to be limited to the exact arrangement shown and described, except as specified in the following claims, in which I claim:

1. In a fuel supply system, the combination of a receptacle having a discharge outlet, and a float controlled valve for said outlet, the arrangement being such that the valve will normally be held in raised position but will be closed when the liquid is discharged at a predetermined rate of flow.

2. The combination of a tank, a discharge pipe for said tank, a valve for controlling the flow through said discharge pipe, a float connected with said valve and adapted to hold it in normally raised position, and manually operative means for opening the valve, the arrangement being such that the valve will be closed when the liquid in the tank falls to a predetermined level or is discharged from the tank at a predetermined rate and will remain closed until manually opened.

3. In an apparatus of the character set forth, the combination of a tank having a discharge outlet, a closure for said outlet, and means for supporting the closure adjacent to the outlet, said means being adapted to hold the closure in open position to permit a predetermined discharge through the outlet and adapted to permit the closure to move to closing position when the rate of discharge exceeds the predetermined rate.

4. An oil tank for supplying fuel to oil burners, having a discharge outlet, a valve for closing said outlet, a float for holding said valve in normally raised position when the tank is filled, and means for holding the valve in predetermined position with respect to the outlet whereby the valve will permit a normal discharge through the outlet but will be drawn to closing position by an excessive discharge.

5. In an apparatus of the character set forth, the combination with a receptacle for holding fluids, having a discharge pipe, of a valve for closing said discharge, a float for holding said valve in substantially balanced

position with respect to the discharge whereby the valve will permit a normal rate of flow from the tank but will be drawn to closed position when the discharge exceeds such normal rate.

6. In an apparatus of the character set forth, the combination of a receptacle hav-

ing an outlet and means for closing the outlet, which means is normally inoperative but which is adapted to close the outlet when liquid is discharged from the chamber at a rate in excess of the normal discharge. 10

JOHN T. JANETTE.
